UNITED STATES PATENT OFFICE

2,509,178

AIR-COOLED ENGINE

Cornelius W. Van Ranst, Dearborn, Mich.

Application February 5, 1945, Serial No. 576,277

4 Claims. (Cl. 123—171)

1

This invention relates to internal combustion engines and particularly to those of the air cooled type, the principal object being the provision of an engine of the type described so constructed and arranged as to be more efficiently cooled than engines heretofore constructed.

Objects of the invention include the provision of a cylinder head of new and improved construction for air cooled internal combustion engines; the provision of a cylinder head for air cooled internal combustion engines so constructed and arranged as to substantially eliminate the dead air pockets found on the exterior surfaces of conventionally formed air cooled cylinder heads; the provision of a cylinder head of the type described providing for a smooth and substantially unbroken flow of air over the exterior surfaces thereof; the provision of a cylinder head of the type described providing a materially increased finned area for the dissipation of heat as compared to conventional constructions in engines of comparable sizes; the provision of a cylinder head of the type described providing finned heat dissipating surfaces separate from those parts thereof called upon to withstand the explosion pressure of the combustible mixture in the engine and so connected to the last-mentioned parts as to be capable of extracting a maximum amount of heat therefrom; the provision of a cylinder head for an air cooled engine so constructed and arranged as to provide a surface forming a part of the combustion chamber of the engine and increasing in its heat transmitting characteristics from the center of said combustion chamber toward the edges thereof and providing means connected to said edges for efficiently dissipating the heat flowing thereto; and the provision of a construction as last described in which the metal of the head is disposed to accommodate a maximum efficiency in heat flow with a minimum of weight.

Other objects of the invention include the provision of an air cooled cylinder head for an internal combustion engine including a portion forming a part of the combustion chamber of the engine and marginal walls integrally connected to such portion and extending outwardly away therefrom and suitably finned to dissipate the heat flowing thereto from the first-mentioned portion; the provision of a cylinder head as above described in which those portions thereof extending away from that portion forming a part of the combustion chamber for the engine form at least in part an enclosure for at least a part of the valve actuating mechanism for the engine;

2

the provision of a cylinder head for an air cooled engine comprising a more or less cup or pan-shaped structure, the bottom of which serves to form a portion of the walls bounding the combustion chamber of the engine and the sides of which are finned to increase the transfer of heat therefrom; the provision of a cylinder head of the construction above described in which a spark plug is located within the cylinder head and the cylinder head is provided with a cover serving with the cylinder head to shield the spark plug and the electrical connection therefor; and the provision of a cylinder head construction as above described in which the exterior surfaces thereof provide a smooth and substantially unobstructed path for the flow of cooling air thereover.

Further objects of the invention include the provision of improved means for guiding the flow of air about an air cooled internal combustion engine; the provision of an air cooled internal combustion engine having fins on the cylinder and head thereof together with means for effecting a distribution of air over said fins varying in volume in accordance with the temperature of different portions thereof; and the provision of a construction as above described including a housing surrounding the cylinder and cylinder head of the engine formed to admit air unrestrictedly along one side thereof, together with means for controlling the egress of the air from the opposite side thereof to provide a flow varying over the length of the cylinder and head more or less proportionally to the variations in temperature over such length.

The above being among the objects of the present invention the same consists in certain novel features of construction and combinations of parts to be hereinafter described with reference to the accompanying drawing, and then claimed, having the above and other objects in view.

In the accompanying drawings which illustrate a suitable embodiment of the present invention and in which like numerals refer to like parts throughout the several different views,

Fig. 1 is a partially broken, partially sectioned end elevational view of an engine embodying the principles of the present invention and taken as, for instance, on the line 1—1 of Fig. 2;

Fig. 2 is a longitudinal sectional view of the engine shown in Fig. 1, taken as on the line 2—2 thereof;

Fig. 3 is a reduced horizontal sectional view taken through the cylinder head of the engine

shown in the preceding views and as on the line 3—3 of Fig. 2;

Fig. 4 is a fragmentary, end elevational view looking in the same direction as the view shown in Fig. 1 but showing the shroud around the cylinder and cylinder head and the aperture therein for controlling the flow of air around the cylinder and the head; and

Fig. 5 is a more or less diagrammatic, vertical sectional view taken diagonally through a cylinder head of the character shown in the preceding views, as, for instance, in the direction of the arrows 5—5 of Fig. 3, to more clearly bring out the principles of the present invention, a portion of a cylinder being shown connected thereto to aid in the explanation of said principles.

The present invention is, of course, adaptable for use in connection with air cooled engines of either the single or multiple cylinder type. For the purpose of simplicity it is shown in the accompanying drawings in connection with a single cylinder engine, as once the principles of the present invention are understood those skilled in the art will readily recognize the application of these principles to engines of the multi-cylinder type and be capable of applying such principles in the design thereof.

It is conventional practice in the formation of cylinder heads for internal combustion engines of the air cooled type to form the head as a cover for the cylinder and as part or all of the combustion chamber which is formed at the outer end of the cylinder, and to provide the ports, rocker arm brackets or other mountings, spark plug bosses, and the like on such surface and to fin all of these parts to withdraw heat therefrom. Air blown over such finned surfaces or otherwise flowing in contact therewith extracts the heat from the fins to provide a cooling effect. Those skilled in the art recognize the fact that such ports or intake and exhaust passages, bosses, brackets and the like act to form pockets which resist the free flow of air through them and serve in effect to provide dead air pockets from which it is extremely difficult to remove the desired amount of heat. The result is that certain portions of these cylinder heads become over-heated and cause hot spots, resulting in pre-ignition of the combustible mixture and other deleterious effects, and often establish limits beyond which the extension of other desirable features of the engine which might otherwise increase the power and efficiency thereof is prohibited. It is, therefore, the principal object of the present invention to provide a cylinder head construction for air cooled internal combustion engines which substantially eliminates such dead air pockets, which provides for an increased flow of heat away from that portion of the cylinder head forming a part of the combustion chamber for the engine, provides an increased area of finned surface for the dissipation of such heat, and provides for the smooth and unbroken flow of air about such finned surface whereby to enable a maximum amount of heat to be extracted therefrom in a simple and efficient manner.

Briefly, the advantages of the present invention are obtained by making the cylinder head of more or less cup or pan-like conformation with the bottom wall thereof closing the end of the cylinder and forming at least a portion of the combustion chamber therefor, the sides of the cup or pan extending away from the cylinder and being exteriorly finned. Preferably such side walls are as smooth and of unbroken curvature as possible,

except for the fins themselves, so that the air flowing about them and between the fins may flow without such abrupt changes in direction as are conducive to the formation of dead air pockets.

In the interests of conserving weight that portion of the head immediately over the cylinder is preferably made thinnest at its center where conveniently possible with increasing thickness towards its marginal edges in the plane of the end of the cylinder, thereby providing a path of increasing thickness radiating outwardly from the center of the combustion chamber towards such margins to enable an increasing amount of heat to flow from the center to such edges. For the same reasons the side walls of the head are preferably of greatest thickness at their points of junction with the bottom wall thereof and decrease in thickness in extending axially away from the cylinder as in such case the amount of heat to be transmitted from the side walls decreases in this direction.

It has been found that the provision of a cylinder head of the type described provides a direct and ready path for the flow of heat from that portion of the head forming a part of the combustion chamber for the associated cylinders and provides a maximum amount of finned areas for the dissipation of such heat into the surrounding air, and thus even in the absence of forced air circulation about the finned areas of the head much more efficient cooling effect is had than is ordinarily capable in conventional constructions. In addition because of the formation of the head the valve stems and their cooperating springs, the rocker arms, brackets, etc. and the spark plug are all located on the interior of the head, the open end of which may be closed by a suitable cover thereby to completely enclose the same. This not only provides extremely efficient radio shielding for the spark plug but further provides an oil and moisture proof enclosure for the valve operating mechanism in the head.

It will be appreciated that the present invention may be applied to air cooled engines regardless of the specific construction of the engine itself and it will, therefore, be appreciated that the particular engine shown in the accompanying drawings and to which the present invention is shown applied is shown in an illustrative and not in a limiting sense.

Referring now to the accompanying drawings it will be noted that the engine there shown comprises a crankcase 10 having a cylinder 12 formed integrally therewith. The crankcase 10 is shown as having one integral end wall and the opposite end open and normally closed by a removable cover member 14. It is assumed that in the particular case shown the crankcase 10 and cylinder 12 is formed from a light metal such as aluminum or magnesium and the cylinder therefor is provided with a steel or other suitable liner such as 16. In the particular construction shown the crankcase 10 is illustrated as being provided with a web 18 spaced from its open face and formed to provide a bearing 20 for the main journal 22 of the crankshaft 24, the latter of which is provided with a pin 26 for receiving the big end of the connecting rod 28, the opposite end of which is pivotally connected to a piston 30 working in the cylinder 16 in a conventional manner. The cover 14 supports an anti-friction bearing 32 which forms a second bearing for the crankshaft spaced from the main journal 22 and outwardly of the bearing 32 a suitable or conventional grease seal 34 is provided in the cap 14. Axially outwardly

of the seal 34 the crankshaft 24 has fixed thereto a flywheel 36 which mounts axially outwardly thereof and in concentric relation with respect thereto a centrifugal fan element of a conventional type generally indicated at 38 and which will be referred to in greater detail presently.

The crankshaft 24 between the web 18 and the cover 14 has fixed thereto a gear 40. As brought out in Fig. 1 a second gear 42, of twice the diameter of the gear 40 and meshing with the gear 40, is mounted on a cam shaft 44 rotatably supported in the crankcase 10 in parallelism with the crankshaft 24. The cam shaft 44 has formed thereon an exhaust cam 46 and an inlet cam 48. Although forming no part of the present invention it may be noted that in radial alignment with the cam shaft 44 and in alignment with each of the cams 46 and 48 the crankcase is provided with a bore, one only of which is shown in Fig. 1, this bore being indicated at 50 and as receiving therein a tappet in the form of a cup 52, the closed end of which is adapted to ride on the corresponding cam 46 or 48. Within each tappet 52 is received a cup-like supporting member 54 having a marginal flange portion at its open end which relatively closely fits the interior of the tappet 52 and which is peripherally relieved below such flange to provide a space 56 between it and the bore of the tappet 52. Below the flange of the support 54 the tappet 52 is provided with one or more holes 58 therethrough which, when the tappet is adjacent its outer limit of reciprocation in the bore 50, becomes aligned with a groove 60 intersecting the bore 50 and to which groove 60 lubricant under pressure is constantly fed during operation of the engine. Such lubricant flows through the opening or openings 58 downwardly into the chamber 56. The support 54 is centrally provided with an axial opening 62 and the bottom of the support 54 is transversely grooved as at 64 to permit the flow of lubricant from the chamber 56 into the opening 62. A hollow push rod 66 extends downwardly into the bottom of the support 54 and is provided with a partially spherical end surface seating in a complementarily shaped surface in the bottom of the support and is provided with an axial opening 68 in constant open communication with the opening 62. The lubricant entering the chamber 56 from the groove 60 may thus flow through the groove 64 and through the openings 62 and 68 into the hollow interior of the push rod 66 and upwardly therethrough to the wearing surfaces of the rocker arms which are mounted in the cylinder head and which will hereinafter be described.

The cylinder 12 is, of course, provided with a multiplicity of radially outwardly directed axially spaced cooling ribs or fins 70 thereon in accordance with conventional practice and it will be understood that in plan view the exterior contour of these fins 70 may be square, round or any other suitable shape.

The upper end of the cylinder 16 is open and is normally closed by a cylinder head constructed in accordance with the present invention. As perhaps best brought out in Fig. 2 this cylinder head comprises a bottom wall 80 extending transversely across the open upper end of the cylinder 12 and secured thereto as by screws 82. The bottom wall 80 may be either round, square or of any other suitable contour in plan view but in a single cylinder engine such as shown is preferably square and is so shown. The bottom wall 80 is marginally surrounded with upstanding

side walls 84 integrally connected thereto, the bottom wall 80 and side walls 84 thus providing in effect a cup-like or pan-like structure, the bottom of which closes the open upper end of the cylinder and forms a portion of the walls of the combustion chamber therefor. In the particular case shown in Figs. 1 and 2 the lower wall 80 is provided over the bore of the cylinder 16 with a pocket 86 (see Fig. 2) the walls of which in this case form the major portion of the walls of the combustion chamber for the cylinder 16.

The bottom wall 80 of the cylinder head is provided with a pair of downwardly opening ports 88 therein opening into the pocket 86 and is formed to provide a passage 90 connected with each of the ports 88 and extending outwardly through the side of the cylinder head, one extending rearwardly as indicated in Fig. 2 and being connected as by a tube such as 92 with a suitable carburetor or the like, and the other being connected as by a tube 92 either exhausting directly into the air or being connected to a suitable muffler or the like. A valve stem guide 96 is formed integrally with each passage 90 and with the bottom wall 80 and is centrally apertured in alignment with the corresponding port 80 for slidable reception of the stem 98 of a conventional poppet valve the head of which is operatively associated with the corresponding port 88. A conventional coil spring 100 surrounds each valve stem 98 and is maintained under compression between a shoulder formed on the corresponding guide 96 and a spring retaining washer 102 mounted on the outer end of each valve stem 98 in a conventional manner. Upwardly extending bracket means 104 are also formed integrally with the wall 80 of the cylinder head and carry at their upper ends a shaft 106 upon which a pair of rocker arms 108 are pivotally supported, the outer ends of the rocker arms lying in contact with the upper ends of the valve stems 98 while the opposite ends thereof are provided with a transversely extending axially adjustable socket head screw 110 which receives the upper ends of the push rods 66 therein.

The wall 80 is provided with a conventional threaded opening therethrough leading into the pocket or combustion chamber 86 in which a spark plug 112, shown in Fig. 1, is threaded with its operative end exposed in the pocket 86. The open upper end of the cylinder head is closed by a cover 114 suitably removably secured thereto. The cover and head are provided with cooperating notches 116 and 118 at one side thereof in which an insulated plug 120 is received. The plug 120 carries a conductor element 122 the inner end of which bears against the terminal at the outer end of the spark plug 112 and the outer end of which bears against a terminal 124 of an electrical ignition cable 126 surrounded by a metal tube 128 socketed at its upper end in a lateral extension 130 of the cylinder head. This means of connecting the cable 126 with the spark plug forms no part of the present invention and is illustrated merely as a means of providing an electrical connection for the spark plug within the cylinder head.

Reference may now be had to Fig. 5 which illustrates in a more or less diagrammatic manner the ideal form of the cylinder head when requiring no consideration of the inlet and exhaust ports and passages, rocker arm brackets, spark plug bosses, combustion chamber or the like. Disregarding these last-mentioned elements the lower wall 80 in such case might be

provided with a flat lower surface closing the open end of the cylinder 12 and in its ideal form and as illustrated in Fig. 5 the bottom wall 80 would be a minimum thickness on the axial line of the cylinder 12 commensurate with the requirements of strength for this part of the head. The wall 80 would increase in thickness from its center toward its lateral margin where it joins the side walls 84 and the side walls 84 would be of maximum thickness at their lower ends where they join the wall 80 and extend upwardly in decreasing thickness to the upper marginal flange 140 where such is provided for reception of the cover 114.

The reasons for this last described form of construction is as follows. It will be appreciated that that portion of the wall 80 overlying the bore of the cylinder 12 and forming a part of the combustion chamber for such cylinder is evenly exposed during operation to the same degree of heat from the explosions of the combustible mixture occurring in the combustion chamber. The heat in this particular case flows through the wall 80 radially outwardly to the marginal side walls 84 and, therefore, at least over the area of the bore of the cylinder 12 is required to be of increasing thickness from the center of the cylinder bore to the edges thereof to provide for, or to accommodate, the increased amount of heat flow at the edges of the bore of the cylinder as compared to the center thereof. As the mass of the wall 80 provided for the flow of heat emanating from the center of the cylinder increases for each increment of distance radially outwardly from the center of the cylinder an ever increasing path for the flow of such heat is thus provided. The heat thus flowing to the periphery of the wall 80 is free to flow upwardly through the side walls 84 which present a maximum amount of mass for reception for such flow of heat, and the heat thus flows upwardly through the side walls 84. These side walls are provided with a multiplicity of integrally formed outwardly projecting cooling ribs or fins 142, preferably horizontally arranged in the particular embodiment shown and which act to thus dissipate the heat flowing through the side walls 84 to the air surrounding the head. This dissipation of heat through the fins 142 obviously decreases the amount of heat which is required to be dissipated in flowing toward the open end of the head so that from a practical standpoint each increment of horizontal cross-sectional area of the head above the wall 80, that is of the side walls 84, may be successively reduced to correspond with the amount of heat to be transmitted therethrough.

It will be understood, of course, that the tapering of the walls 80 and 84 as particularly brought out in Fig. 5 is theoretically the best arrangement for obtaining a maximum heat flow with a minimum amount of metal and that from a practical standpoint, and particularly where the mass of metal is more or less unimportant, this tapered formation may not be of material importance from the standpoint of obtaining the desired rapid dissipation of heat from the head. It will also be appreciated that, and as brought out particularly in Figs. 1 and 2, the necessary provision of inlet and exhaust passages, rocker arm brackets, combustion chamber shapes or profiles, and the like may introduce many difficulties particularly in connection with providing the ideal variation of thickness in the bottom wall 80 of the head, but nevertheless where weight is of primary importance the variation in

thickness of the bottom wall of the head to correspond with the conditions shown in Fig. 5 may at least be approached by careful design. Other requirements may also force modifications of the ideal conditions. For instance, and as brought out in Fig. 1, oil drain holes such as 132 provided for drawing oil tending to accumulate in the cylinder head and returning it through a tube such as 134 to the crankcase 10, and holes such as 136 for passage of the push rods 66 through the cylinder head and for reception of the upper ends of the tubular housings 138 for the push rods 66, may require modification of the disposition of the metal of the head to compensate for the heat flow path thus interrupted, or at least varied, by the provision of such holes. These various departures from the ideal conditions will be readily appreciated by those skilled in the art.

As previously mentioned the cross-sectional contour of the bottom wall 80 and side walls 84 of the cylinder head may be round, square or of any other desired shape, that shown being square and being preferable in many cases particularly in view of the fact that the valve mechanisms and spark plugs may require a considerable volume within the head to accommodate the same. Likewise the contour of the peripheral edges of the fins 142 may be any shape desired regardless of the peripheral shape of the wall 80 and the side walls 84 but in the case shown are square the same as the side walls 84.

The important thing to note in connection with the above described construction is that instead of only providing a bottom wall such as 89 and providing cooling fins directly upon it and upon the inlet and exhaust passages 90, the valve guide bosses and the like as in conventional cylinder heads for air cooled engines, in which the amount of fin area is more or less restricted in any case and which inevitably results in the formation of so-called dead air pockets through which it is difficult to say the least to insure a satisfactory flow of cooling air, the construction provided by the present invention acts to draw the heat imparted to the wall 80 to its marginal portions and there conducts it up the side walls 84 whose exposed outer surfaces may be made to present a materially greater area than would ever be present on the upper surface of the wall 80, the passages 90, etc., and form these side walls with smooth surfaces amply finned for the dissipation of heat therefrom. As a result cylinder heads constructed in accordance with the present invention have been found to be of materially greater efficiency in the dissipation of heat from the cylinder head than conventional constructions, permitting a lower average working temperature of the cylinder head in engines of corresponding size, the elimination of localized hot spots as inevitably occur in cylinder heads of conventional construction because of the dead air pockets heretofore described, and enables other features advantageous to the increased power and efficiency of the engine to be carried forward from a point to which they are limited in engines having cylinder heads of conventional construction, thus resulting in an engine of increased power and efficiency for corresponding sizes.

Where cylinder heads of the present invention are applied to multi-cylinder engines the design of the head may be varied to correspond depending upon whether the engine is of the individual cylinder type or the en bloc type. In other words where the engine is of the individual cylinder type, 75 then each individual cylinder may be provided

with an individual head as in the particular case shown and described, and where the engine is of the en bloc type then a cylinder head of corresponding length may be provided, the head in such case being provided with two side and two end walls suitably exteriorly ribbed in the same manner as the individual cylinder head here described.

It has been found that cylinder heads constructed in accordance with the present invention will operate in most cases as efficiently without forced air cooling as conventional types of cylinder heads will operate with forced air cooling. This, of course, is a result of the feature of the present invention providing rapid withdrawal of heat from the center to the marginal portions of the head and dissipating this heat to extended surfaces having smooth exterior contours providing for the ready and natural flow of air over them and ribbed or finned to increase the heat dissipating qualities thereof. The use of forced air circulated over the finned areas of the cylinder and head does, of course, serve to greatly increase the dissipation of heat from the cylinder head and is ordinarily desirable, particularly in the case of high output engines.

In the last-mentioned connection and in accordance with another phase of the present invention means are provided for controlling the flow of forced circulation of air over the finned areas of the engine in accordance with the needs of each portion. In other words it will be appreciated that the lower portions of the cylinder will not become as hot as the outer portions thereof and, therefore, do not require the volume of flow of cooling air that the outer portions require. Additionally, the cylinder head usually requires the dissipation of a much greater amount of heat than even the upper end of the cylinder and, accordingly, requires a correspondingly greater amount of flow of cooling air than such upper end of the cylinder. In accordance with this phase of the present invention the cooling air is fed to one side of the cylinder and the cylinder head and preferably in a manner permitting an equal flow to all portions in the length of the cylinder and cylinder head, and the cylinder and cylinder head are shrouded for the flow of air therearound and the egress of the air from the shroud is controlled to provide for the desired volume of flow of air over the separate portions of the length thereof. The means by which this is accomplished will now be explained in connection with this feature of the invention.

Referring now to Fig. 2 it will be noted that a sheet metal housing or shroud 150 is extended into surrounding relationship with respect to the flywheel 36 and fan 38. It is provided with an inlet opening 151 in axial alignment with the flywheel 36 and fan 38 and with a cooperating collar 152 which projects axially a short distance into the fan 38. The shroud 150 is generally spaced from the flywheel 36 and fan 38 and is provided with a vertically extending portion 153 sealed at its lower edges about the crankcase and projecting upwardly around the cylinder 12 and the cylinder head and is sealed at its upper end to the marginal flange 140 at the upper end of the head. As brought out in Fig. 2 the shroud 153 is spaced from the cylinder 12 and head on the flywheel side of the engine so as to provide a vertical passage 154 through which the air drawn through the opening 151 and discharged by the fan 38 interiorly of the shroud 150 may freely flow vertically for the full length of the

cylinder and cylinder head. As best brought out in Fig. 3 the shroud 153 relatively closely fits the fins 70 and 142 along the sides and lefthand face of the cylinder and cylinder head and, as brought out in Fig. 4, centrally of the lefthand face of the engine the shroud 153 is provided with a vertically extending notch 156 therein. This notch is of a narrow V-like conformation, that is its narrowest dimensions are at the bottom thereof adjacent the lower edge of the shroud 153 and gradually increases in width toward the top. Around the exhaust passage 90 which projects out therethrough the shroud 153 is spaced so as to provide for the flow of air therearound.

It will be appreciated that with the construction above described and with the air from the fan 38 capable of flowing freely vertically through the passage 154, the relative volume, or proportion of the total amount of air discharged by the fan 38, which flows between each adjacent pair of fins 70 and 142 is controlled by the width of the notch 156 at the discharge side of each such pair. Thus a minimum amount of air may flow around the lower of the fins 70 and escape through the lower portion of the notch 156 while a greater amount of air may flow through the fins adjacent the upper end of the cylinder and escape through the corresponding portion of the notch 156, and an even greater amount of air may flow around the fins 142 of the cylinder head and escape out through the upper portion of the notch 156. Obviously the shape of the notch 156 may be varied to vary the volume of flow of air at any particular point in the height of the notch to correspond with the amount of heat to be dissipated from the corresponding portion of the length of the cylinder and cylinder head assembly. It will be appreciated that by this method a simple and effective means is provided for accurately and efficiently controlling the flow of the cooling air to obtain optimum cooling conditions for the engine as a whole.

Having thus described my invention, what I claim by Letters Patent is:

1. An air cooled cylinder head for an internal combustion engine comprising a member adapted to be secured in sealing relation with respect to the open end of an engine cylinder and having a single transverse wall adapted to form a part of the combustion chamber therefor, inlet and exhaust passages formed integrally with said wall and opening therethrough, valves carried by said wall for controlling the flow of fluid through said passages, a spark plug carried by said wall within the margins thereof in operative relation with respect to the combustion chamber adapted to be bounded thereby, a continuous side wall formed integrally with said transverse wall and extending completely around the margins thereof and projecting away from that face thereof serving as a part of a combustion chamber, said side walls encompassing said spark plug, valves and at least a portion of said passages, a plurality of generally spaced cooling fins formed integrally with said walls on the outer surface thereof, and a closure removably secured to the free margins of said side walls and sealing said valves and spark plug within said side walls.

2. An air cooled cylinder head for an internal combustion engine having a cylinder provided with an open end comprising, in combination, a member devoid of external lateral pockets comprising a single transverse wall which is adapted to close the open end of said cylinder and to form a part of the combustion chamber therefor and

11

side walls formed integrally with said transverse wall extending continuously around the margins thereof and projecting perpendicularly to the plane of said transverse wall, inlet and exhaust passages for said combustion chamber formed integrally with said member and housed at least in part therein, valves for controlling said passages guided in and carried by said member, rocker arms for operating said valves supported and housed within said member, a removable closure for the open end of said member, and a plurality of generally parallel and generally spaced integral cooling fins projecting outwardly from the outer surfaces of said side walls of said member.

3. An air cooled cylinder head for an internal combustion engine having a cylinder provided with an open end comprising in combination, a member having a single transverse wall which is adapted to close the open end of said cylinder and to form a part of the combustion chamber therefor and integral side walls projecting approximately perpendicularly to said transverse wall continuously around the outer margins thereof, inlet and exhaust passages for said combustion chamber formed integrally with said transverse wall and housed at least in part therein, valves for controlling said passages guided and carried by said transverse wall, rocker arms for operating said valves supported and housed within said transverse wall, a removable closure for the open end of said member, and a plurality of generally parallel and generally spaced cooling fins projecting outwardly from the outer surfaces of said side walls and formed integrally therewith, said side walls increasing in thickness from the free edges thereof toward their line of junction with said transverse wall.

4. A cylinder head for an internal combustion

12

engine having a cylinder provided with an open end comprising, in combination, a member having a single transverse wall which is adapted to be secured in sealing relationship with respect to said open end of said cylinder and to form a portion of the combustion chamber therefor and continuous side walls formed integrally with and projecting axially outwardly from the peripheral margins of said transverse wall, a multiplicity of generally spaced cooling fins integrally joined to the outer faces of said side walls, said transverse wall generally increasing in thickness from the center thereof toward the margins thereof and said side walls generally decreasing in thickness from their point of connection with the margins of said bottom wall toward their free edges.
